UNITED STATES PATENT OFFICE.

KARL A. SIMMON, OF EDGEWOOD PARK, AND LYNN G. RILEY, OF WILKINSBURG, PENNSYLVANIA, ASSIGNORS TO WESTINGHOUSE ELECTRIC AND MANUFACTURING COMPANY, A CORPORATION OF PENNSYLVANIA.

CASING FOR CONTROL APPARATUS.

1,308,119.

Specification of Letters Patent.

Patented July 1, 1919.

Application filed October 10, 1914. Serial No. 866,161.

To all whom it may concern:

Be it known that we, KARL A. SIMMON, a citizen of the United States, and a resident of Edgewood Park, in the county of Allegheny and State of Pennsylvania, and LYNN G. RILEY, a citizen of the United States, and a resident of Wilkinsburg, in the county of Allegheny and State of Pennsylvania, have invented a new and useful Improvement in Casings for Control Apparatus, of which the following is a specification.

Our invention relates to casings for control apparatus, and especially to certain structural features of motor-controlling devices of the well-known unit-switch type and the like.

The object of our invention is to provide a device of the above-indicated character which may be mounted in any convenient location and which shall embody a plurality of stationary frame members and hinged cover members collectively adapted to form a suitable number of separate apparatus-containing compartments.

The total cost of manufacturing and installing such a device, the weight of the apparatus and the space required underneath a railway vehicle are materially reduced, and the accessibility of the apparatus after installation is greatly increased.

Our invention is characterized by a compact, rugged rectangular unitary structure which is relatively light in weight and which may be readily installed, inspected and repaired. Moreover, the compartments on opposite sides of each end-plate are substantially gas tight, thereby being adapted to prevent the passage of conducting vapors between the various pieces of apparatus.

In the accompanying drawings, Figures 1, 2 and 3 are views in plan, in side elevation and in end elevation, respectively, of a "switch group" constructed in accordance with our invention; and Figs. 4, 5 and 6 are views in plan, in side elevation and in end elevation, respectively, of a modified form of "switch group" embodying our invention.

Referring to Figs. 1, 2 and 3 of the drawings, the structure shown comprises a "switch group" provided with a suitable supporting frame 1 of customary construction that is provided, at its respective ends, with a plurality of end plates 2 and 3, which, respectively, have integrally connected top-

cover members 2^a and 3^a of substantially the same width as the body portion of the "switch group" and through which a plurality of conductor-receiving openings 2^b and 3^b and supporting bolt-receiving openings 2^c and 3^c respectively extend. A plurality of complementary right-angled, suitably internally insulated cover members 4 are hinged to the body portion of the "switch group" at the points 4^a on each end of the group and are adapted to be fastened together to form suitable end compartments, as hereinafter described, by means of appropriate latch members 4^b. A plurality of cover members 5, which are adapted to inclose the sides of the body portion of the "switch group", are suitably removably associated with the supporting frame member 1 at the points 5^a and are secured together by means of one or more latches 5^b.

The sets of cover members 4 and 5 are thus each centrally divided in a plane normal to the end-plates, which makes for ready accessibility to the interior of the casing. Each cover member 4 comprises three walls severally disposed normally to the other walls, while each cover member 5 embodies two right-angled walls. Thus, distinct and completely-inclosed compartments for the reception of any desired control apparatus are provided.

Referring now to the modified structure illustrated in the remaining figures; Figs. 4, 5 and 6 show a switch group comprising a suitable supporting frame 18 that is provided with side openings through which main-circuit conductors 19 are adapted to pass; a plurality of end plates 20 and 21, for the respective ends of the frame 18, that are respectively provided with suitable integral top-cover members 20^a and 21^a; a plurality of right-angled cover members 22, similar to those described in connection with Figs. 1 and 2, which are suitably hinged upon the body portion of the "switch group" at points 22^a and may be suitably centrally secured together by means of latches 22^b; a plurality of similar cover members 23, for the other end plate 21, which are suitably hinged to the body portion of the switch group at the points 23^a and may be fastened together by means of suitable latches 23^b; a plurality of side-cover members 24 which may be hinge-secured to

the frame member 18 at the points 25; and an arcing box AB comprising a plurality of arcing chutes AC for certain of the unit switches comprised within the body portion 5 of the "switch group." The switch group, as a whole, may be supported, by means of channel irons 26, upon the underside of a railway vehicle floor 27, or it may be supported in any other well-known manner.

10 In the control apparatus hereinbefore described, we have provided a switch group comprising a pair of end plates, and a plurality of suitable cover members, for constituting, with the end-plates, a plurality of 15 suitably insulated compartments at each end of the switch group, which compartments are adapted to contain various pieces of control apparatus and maintain them completely isolated from each other, whereby 20 they are, in effect, separately mounted; although the switch group, as a whole, comprises a symmetrical, compact, unitary structure, the advantages of which have already been pointed out.

25 We do not wish to be restricted to the specific structural details or arrangement of parts herein set forth, but desire that only such limitations shall be imposed as are indicated in the appended claims.

30 We claim as our invention:

1. A casing comprising a frame, a plurality of end plates secured to the frame, side cover members hinged to the frame and adapted to inclose the bottom and sides of 35 the space between said end plates, and cover members hinged to the said end plates and

adapted to form distinct compartments therewith.

2. A casing comprising a frame, an end member secured thereto and having an outwardly extending top portion normal to the main portion thereof, and a two-part cover member divided in a plane normal to both portions of the said end member and adapted to form a distinct compartment therewith, said cover members being hinged to the main portion of the said end member. 40

3. A casing comprising a frame, a plurality of end plates secured to the frame and provided with outwardly extending top portions, a cover adapted to fit between the end plates and below the frame, a cover adapted to fit between the end plates and above the frame, and a cover adapted to coöperate with one of the end plates to provide a distinct compartment. 50

4. A casing comprising a frame, end plates secured to the said frame, complementary cover members hinged to the frame and divided in a plane centrally normal to the 60 end plates, complementary cover members hinged to the said end plates and divided in the said normal plane.

In testimony whereof we have hereunto subscribed our names this 9th day of Oct., 65 1914.

KARL A. SIMMON.
LYNN G. RILEY.
